US00D741663S

(12) United States Design Patent
Hansen

(10) Patent No.: US D741,663 S
(45) Date of Patent: * Oct. 27, 2015

(54) BEVERAGE SLEEVE

(71) Applicant: NESNAH, LLC, Omaha, NE (US)

(72) Inventor: Mike Hansen, Omaha, NE (US)

(73) Assignee: NESNAH, LLC, Omaha, NE (US)

() Term: 14 Years

(21) Appl. No.: 29/462,479

(22) Filed: Aug. 5, 2013

(51) LOC (10) Cl. 07-06

(52) U.S. Cl.

USPC D7/625

(57) CLAIM

The ornamental design for a beverage sleeve, as shown and described.

DESCRIPTION

FIG. 1 is a top, front perspective view of a beverage sleeve showing my new design;

FIG. 2 is a top plan view thereof;

FIG. 3 is a front elevational view thereof;

FIG. 4 is a right elevational view thereof;

FIG. 5 is a rear elevational view thereof;

FIG. 6 is a left elevational view thereof; and,

FIG. 7 is a bottom plan view thereof.

The broken lines shown in FIGS. 1–7 represent portions of the beverage sleeve that form no part of the claimed design.

1 Claim, 4 Drawing Sheets
